(57) **CLAIM**

I claim the ornamental design for pastry wheel, as shown and described.

DESCRIPTION

FIG. 1 is a perspective view of a pastry wheel, showing my new design.

FIG. 2 is a front view of the pastry wheel, the back view being identical.

FIG. 3 is a left side view of the pastry wheel.

FIG. 4 is a right side view of the pastry wheel.

FIG. 5 is a top view of the pastry wheel; and,

FIG. 6 is a bottom view of the pastry wheel.

Portions shown in phantom, including the tread and shape of a cutting wheel and blades, form no part of the claimed invention.
